US0D1100206S

(12) **United States Design Patent** (10) **Patent No.:** **US D1,100,206 S**
(45) **Date of Patent:** **** Oct. 28, 2025**

(54) **INSTRUMENT**

(71) **Applicant:** **Roche Molecular Systems, Inc.**,
Pleasanton, CA (US)

(72) **Inventors:** **Connor Fitch**, Vista, CA (US); **John Bernard Gorman**, Carlsbad, CA (US);
Danielle Gadbois, San Diego, CA (US); **David Brown**, San Marcos, CA (US); **Jinyu Yang**, Los Angeles, CA (US); **Joseph Leon Lutgen**, Costa Mesa, CA (US); **Dave Hines**, North Tustin, CA (US)

(73) **Assignee:** **Roche Molecular Systems, Inc.**,
Pleasanton, CA (US)

(**) **Term:** **15 Years**

(21) **Appl. No.:** **29/862,521**

(22) **Filed:** **Dec. 9, 2022**

(51) **LOC (15) Cl.** **24-02**

(52) **U.S. Cl.**

USPC **D24/216**

(57) **CLAIM**

The ornamental design for an instrument as shown and described.

DESCRIPTION

FIG. 1 is a perspective view of a first embodiment of an instrument our new design;

FIG. 2 is a front elevation view thereof;

FIG. 3 is a left side view thereof;

FIG. 4 is a right side view thereof;

FIG. 5 is a perspective view of a second embodiment of an instrument our new design;

FIG. 6 is a front elevation view of the second embodiment;

FIG. 7 is a left side view of the second embodiment; and,

FIG. 8 is a right side view of the second embodiment.

The broken lines in the drawings illustrate portions of the instrument that form no part of the claimed design.

1 Claim, 8 Drawing Sheets
